T. W. POST,

HEADLIGHT,

APPLICATION FILED SEPT. 12, 1917.

1,376,575.

Patented May 3, 1921.

UNITED STATES PATENT OFFICE.

TRUMAN W. POST, OF PROVIDENCE, RHODE ISLAND, ASSIGNOR TO WILLYS CORPORATION, OF TOLEDO, OHIO, A CORPORATION OF DELAWARE.

HEADLIGHT.

1,376,575.

Specification of Letters Patent. Patented May 3, 1921.

Application filed September 12, 1917. Serial No. 190,975.

To all whom it may concern:

Be it known that I, TRUMAN W. Post, a citizen of the United States, residing at Providence, in the county of Providence and 5 State of Rhode Island, have invented certain new and useful Improvements in Headlights, of which I declare the following to be a full, clear, and exact description.

This invention relates to improvements in 10 headlights and more particularly to automobile headlights of the tilting reflector type.

There are several things which are essential to the construction of a satisfactory 15 automobile headlight. The highly polished surface of the parabolic reflector should be protected from moisture because if this is not done, the reflecting surface will soon become tarnished and the illuminating power 20 of the headlight will be greatly diminished. The parabolic reflector is usually made of very thin metal and it is necessary that the parabolic shape of the reflector be maintained, because if this is not done, a distortion 25 of the reflector will occur, which will result in an uneven and unequal reflection of the light. In the stationary reflector type of headlight, the reflector is clamped to the casing so that its parabolic shape is maintained by the casing, and the open end of 30 the reflector is closed by the lens covering the front of the casing, so that the reflecting surface is protected from moisture. However, when the reflector is mounted within 35 the casing so as to tilt therein, these methods of protecting the reflecting surface and maintaining the parabolic shape of the reflector are no longer applicable, because the reflector must be so mounted as to be free to 40 move relative to the casing. The lens which covers the front of the casing does not adequately serve to protect the reflecting surface of the reflector from moisture, because the casing is not moisture proof and moisture 45 can enter through the openings for the electrical connections, and in other places in the headlight casing so that it is necessary to provide some additional means for protecting the reflector from moisture, in a 50 tilting reflector type of headlight. It is also necessary to provide means for maintaining the parabolic shape of the reflector, because the means which are used in the stationary reflector type are not applicable in the tilting reflector type.

It is furthermore highly desirable to balance the tilting reflector as nearly as possible, because this minimizes the amount of force necessary to move the reflector and minimizes the effect of the vibratory movement to which the headlight is subjected when the vehicle is driven over uneven roads.

The primary object of my invention is to provide an automobile headlight of the tilting reflector type, in which the reflector is so constructed and mounted within the casing as to protect the reflecting surface of the reflector from moisture, and to maintain the parabolic shape of reflector at all times. A further object of my invention is to so construct and mount the reflector that it will be more nearly balanced than has heretofore been possible.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawings forming a part thereof, in which:

Figure I is a vertical, sectional view, taken through a headlight embodying my invention.

Fig. II is a fragmentary, sectional view, taken substantially on the line II-II of Fig. I.

Fig. III is a fragmentary, detail view, similar to Fig. II, but showing the reflector and the plate covering the front of the reflector in full lines.

In the drawings, similar reference numerals refer to similar parts throughout the several views, and the sectional views are taken looking in the direction of the arrows at the ends of the section lines.

Considering the numbered parts of the drawing, I have shown a headlight comprising a casing 10, the open end of which is closed by a lens 11 carried by the ring 12. The parabolic reflector 13 is mounted within the casing 10, so as to swing on a horizontal 110

axis and said parabolic reflector carries the usual light bulb 14, having a socket 15, connected with a connector 16, carried by the rear end of the casing 10 by means of the 5 wires 17. A forwardly facing annular groove 18 is formed in the forward edge of the reflector 13 and a packing ring of wicking, 19, or other suitable material, is disposed in said groove. Said wicking may be 10 held in place by applying a coating of shellac if so desired. A glass plate or pane 20 closes the open forward end of the reflector 13, and its rear face lies against the wicking 19 disposed in the groove 18. Said 15 pane is held in place by means of the split ring 21, which is channel-shaped in form, and embraces the edge of the pane 20, and the edge of the reflector 13, as clearly shown in Fig. I of the drawing. As I have stated 20 above, this ring is split and its ends are provided with the radially extending ears 22, through which the bolt 23 passes by means of which the ears 22 may be drawn together so as to clamp the pane 20 in place, 25 closing the reflector 13. This provides an effective moisture-proof closure for the forward end of the reflector and adequately prevents any moisture getting at the polished reflecting surface so as to tarnish 30 the same.

Trunnions 24 are mounted upon the ring 21 at diametrically opposite points thereon, and said trunnions are journaled in bearings 26 carried by the members 25 secured to the 35 casing, so that the reflector 13 is journaled on a horizontal axis as clearly appears from Fig. II of the drawing. The axis on which the reflector is journaled passes a slight distance back of the pane of glass 20, so that 40 said pane of glass serves to partially balance the weight of the reflector and the weight of the socket 15 and the light bulb 14. As a result, a reflector constructed in accordance with this invention is nearly 45 balanced.

A clip 27 embraces the socket 15 in the rear of the reflector 13, and said clip is connected to the upper end of the wire 28, which is movable in a sleeve 29 disposed in a boss 50 30, secured to the casing 10. Said sleeve 29 is held in place relative to the boss 30 by means of a set screw 31, and the sleeve may be adjusted relative to the boss and the casing by loosening the set screw 31. The reflector 13 may be tilted within the casing 10 55 by movement of the wire 28 in a manner which is understood, and which forms no part of my present invention.

From the description of the parts given 60 above, the operation of my device should be very readily understood. The pane of glass 20 coöperating with the packing ring 19 of wicking makes a moisture-proof joint and closure for the reflector 13, so that no

moisture can get at the polished surface 65 of the reflector and it is protected against tarnishing. The pane of glass 20 and the ring 21, which holds it in place, also serves to maintain the outer edge of the reflector 13 in a true circle, so that the parabolic 70 shape of the reflector 13 is maintained against any distortion. It will be seen that the pane of glass and the clamping ring 21, which holds it in place, has a double 75 function, in that it serves to protect the reflector from moisture and, at the same time, serves to stiffen the reflector and insure its maintenance in its true parabolic shape. This pane of glass 20 and the clamping ring 21 also have an additional 80 function in that the great bulk of it is disposed in front of a vertical plane passing through the axis, on which the reflector is journaled, so that its weight serves to partially 85 balance the weight of the reflector 13 and the socket 15 and light bulb 14. This balancing of the reflector is very desirable in that it minimizes the force necessary to swing the reflector on its axis, and also minimizes the effect of the vibratory movement 90 to which the headlight is subjected, as the automobile on which the headlights are mounted is driven over rough or uneven surfaces. It will be seen that, in the construction which I have illustrated and 95 described in this specification, I have provided a construction, which embodies the three highly desirable features, which I have heretofore pointed out, in that this construction protects the highly polished surface of the reflector from moisture, stiffens the reflector so that it will always be maintained in its true parabolic shape and more nearly approximates a true balancing of the reflector relative to its axis.

I am aware that the particular embodiment of my invention, which I have here shown and described, is susceptible of considerable variation without departing from the spirit thereof, and, therefore, I desire 100 to claim my invention broadly, as well as specifically, as indicated by the appended claims.

Having thus described my invention, what I claim as new and desire to secure by 115 Letters Patent is:

1. A device of the class described, comprising the combination of a casing; a reflector mounted to tilt therein, the forward edge of said reflector being provided with 120 a forwardly facing annular groove; a packing ring disposed in said groove; a pane of glass having its periphery engaging said packing ring; and a split channel-shaped ring embracing the forward edge of said 125 reflector and the periphery of said pane, and clamping said pane of glass in place against said packing ring, closing the open

end of said reflector and maintaining the circular shape of the rim of the same; and means for tilting said reflector.

2. A device of the class described, comprising the combination of a casing; a reflector therein; a pane of glass; a split channel-shaped ring, embracing the forward end of said reflector and the periphery of said glass, and adapted to clamp said

pane of glass to the forward edge of said reflector to close the open end of said reflector; a pair of trunnions mounted on said ring at diametrically opposite points thereof; bearings for said trunnions carried by said casing; and means for tilting said reflector.

In testimony whereof I affix my signature.
TRUMAN W. POST.
